UNITED STATES PATENT OFFICE.

CHRISTOPHER C. SHELBY, OF PATERSON, NEW JERSEY.

CLASP.

SPECIFICATION forming part of Letters Patent No. 340,831, dated April 27, 1886.

Application filed February 24, 1886. Serial No. 193,055. (No model.)

To all whom it may concern:

Be it known that I, CHRISTOPHER C. SHELBY, of Paterson, in the county of Passaic and State of New Jersey, have invented certain new and useful Improvements in Clasps; and I do hereby declare the following to be a full, clear, and exact description of the same, reference being had to the accompanying drawings, forming part of this specification, and to the figures and letters of reference marked thereon.

My invention relates to clasps adapted for use in connection with that class of stocking-supporters which consist of pieces of webbing secured to a belt or the waistband of a garment, and provided with clasps on their lower ends for connecting with the stocking of the wearer; and it consists in a certain improved construction, which I will now proceed to describe.

In the drawings, Figure 1 is a view showing my improved clasp open applied to a stocking-supporter. Fig. 2 is a similar view showing it fastened to a stocking. Fig. 3 is a sectional view on the line *x x*; Fig. 4, a similar view on the line *y y* of Fig. 2, and Fig. 5 a view of a modification.

Similar letters of reference in the several figures indicate the same parts.

A represents the depending webbing of the stocking-supporter, and B the stocking to be attached thereto.

C represents the clasp, consisting of the base-plate D, having the transverse slot *d* at its forward end and the ears and projecting teeth *d'* at its other end, and it is further provided with a central longitudinal slot, D', extending nearly its entire length, and terminating at the forward end in an enlarged recess, D''.

E is a locking-plate, having the slot *e* therein extending from the rear end forward and terminating a short distance from the end, the ends of the two arms thus formed being pivoted to the base-plate D about midway of its length by being narrowed and bent around bars *d''*, formed by making two small perforations in the plate on either side of the central longitudinal slot, D'.

At its forward end the plate E is provided with a button or projection, F, slightly smaller than the recess D'', adapted, when the plate is swung down, to project through said recess;

or this projection may be made integral with the plate, as shown in Fig. 5.

G is a button or slide, having the enlarged ends and narrow shank placed in the slots in the base and locking plates, and adapted when moved forward, by reason of the broad ends, to press the locking-plate down upon the base-plate and the button on the former through the recess D'', as will be readily understood. When the button G is moved to the rear end of the slot, the plate E can be swung up on its pivots to the position shown in Fig. 1.

The clasp thus described is attached to the webbing of the supporter in the following manner, and to the stocking in a manner to be described further on: The webbing is inserted through the slot *d* in the forward end of the base-plate from the upper side and then pulled through to the rear end of the plate, where it and the main portion of the webbing are secured together and to the plate by the teeth on the plate and the ears *d'*, which are bent down upon them. By this means the under side of the plate is prevented from coming in contact with the garments of the wearer and the liability of their becoming soiled lessened.

When the stocking is to be secured to the supporter, the locking-plate E is swung up to the position shown in Fig. 1, (the button G being moved to the rear of the slot for this purpose,) and the fabric placed upon the base-plate over the recess D'' therein. The plate E is now brought down, the projection F forcing the fabric through the recess in the plate and causing it to bite on the edges of the recess and the button, as shown in Fig. 3. Then the slide G is moved forward in the slot, securely clamping the two plates and the fabric between them in position. Where it is desired to remove the fabric, the slide is moved back, the locking-plate swung up, and it is withdrawn.

The advantages of my improved clasp over others of its class are obvious.

The whole device is very simple, consisting of only three pieces, which are simple in themselves and can be cheaply made, being stamped out of sheet metal and readily put together by an unskilled workman. The fabric is secured tightly to the clasp, not by spring-pressure and teeth projecting into it, but by a bight around a smooth surface; and, further, the

wearer's clothing is prevented by the webbing from contact with the metal, which otherwise would soil them.

While I have described my improved clasp 5 as applied to stocking-supporters, it is obvious that it is adapted to all uses to which clasps are ordinarily applied.

I claim as my invention—
1. The combination, with the base - plate 10 adapted to be secured to the webbing and having the longitudinal slot and the recess near one end thereof, of the locking-plate pivoted to the base-plate and having a longitudinal slot corresponding to that in the base - plate, and the stud or button at its end adapted to co-operate with the recess in the base-plate and secure the fabric, and the slide or button

adapted to slide in the slots in the base and locking plates and hold the two plates firmly together, substantially as described. 20

2. The combination, with the webbing A, the base-plate having the transverse slot at its forward end and the ears or teeth at its rear end for securing the end of the webbing to the body of the latter and to the plate, and having 25 also the longitudinal slot and recess, of the pivoted locking - plate having the button or projection and the slide for securing the two plates together when the latter is swung down, substantially as described.

CHRISTOPHER C. SHELBY.
